UNITED STATES PATENT OFFICE.

THOMAS L. MONAGHAN, OF NEW YORK, N. Y.

SWIMMING MITT OR GLOVE.

1,023,581.

Specification of Letters Patent.

Patented Apr. 16, 1912.

Application filed December 20, 1911. Serial No. 666,868.

To all whom it may concern:

Be it known that I, THOMAS L. MONAGHAN, a citizen of the United States, and a resident of the city of New York, borough 5 of Manhattan, in the county and State of New York, have invented a new and Improved Swimming Mitt or Glove, of which the following is a full, clear, and exact description.

10 The invention relates to swimming appliances and its object is to provide a new and improved swimming mitt or glove for convenient attachment to the hand of a person with a view to keep the fingers in the proper position thus greatly aiding a person in learning to swim. In order to accomplish the desired result, use is made of a mitt body of a length and width to accommodate the four fingers of a person's hand, with a view to hold the 15 said fingers in extended position and one alongside the other, a retaining band extending longitudinally from the rear upper end of the mitt body, and a wrist band on the rear end of the said retaining band and 20 adapted to encircle the wrist of the person using the mitt, the ends of the wrist band being provided with fastening means for holding the wrist band in closed position around the wrist of the user.

25 30 A practical embodiment of the invention is represented in the accompanying drawings forming a part of this specification, in which similar characters of reference indicate corresponding parts in both views.

35 Figure 1 is a plan view of the swimming mitt or glove; and Fig. 2 is an inverted plan view of the same.

It is well known that beginners keep the fingers of the hands spread apart when 40 learning to swim and consequently the hand does not form a paddle as it should be in propelling the person forward in the water during the swimming stroke, and in order to keep the fingers in stretched position and 45 one alongside the other is the object of the mitt presently to be described in detail, so that a proper paddle is formed for propelling the person forward.

The body A of the swimming mitt is 50 made of rubber or other suitable material not liable to be affected by being immersed in water, and the said body A is made of a

length and width to accommodate the four fingers of the hand of a person, as plainly indicated in the drawing, it being understood that the rear end of the mitt terminates in a line transverse to the junction of the forefinger with the thumb so that the thumb is outside of the body A. A retaining band B is secured to the upper rear end 55 of the body A and extends rearwardly over the back of the hand to the wrist, and on the rear end of the said retaining band B is secured a wrist band C adapted to encircle the wrist. The ends of the wrist band C are 60 adapted to be fastened together at the under side of the wrist by the use of suitable fastening means such for instance as a button D and buttonhole D', or spring buttons and 65 sockets of the usual construction. 70

By the arrangement described the body A can be readily placed in position on the user's hand at the time the wrist band C is open, and after the body A has been drawn in position on the hand so as to enclose the four fingers then the band B is drawn rearward and the wrist band C is caused to encircle the wrist and is closed by the fastening device D, D', so as to securely 75 hold the mitt or glove in position on the 80 user's hand.

Having thus described my invention, I claim as new and desire to secure by Letters Patent:

A mitt having a body of a length and 85 width for accommodating the four fingers of a person's hand to hold the said fingers in extended position and one alongside the other, a retaining band extending longitudinally from the rear upper end of the 90 mitt body, and a wrist band on the rear end of the said retaining band and adapted to encircle the wrist of the person using the mitt, the ends of the wrist band being provided with fastening means for holding the 95 wrist band in closed position around the wrist of the user.

In testimony whereof I have signed my name to this specification in the presence of two subscribing witnesses.

THOMAS L. MONAGHAN.
